CLAIM

The ornamental design for wax rose candle on a stick, as shown and described.

DESCRIPTION

FIG. 1 is a front elevational view of a wax rose candle on a stick showing my new design;
 FIG. 2 is a right side elevational view thereof;
 FIG. 3 is a left side elevational view thereof;
 FIG. 4 is a rear elevational view thereof;
 FIG. 5 is a top plan view thereof; and,
 FIG. 6 is a bottom plan view thereof.
 The stick in FIGS. 1-4 is shown broken away to indicate indeterminate length.
